FREDERICK P. POOLE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC-LAMP SOCKET.

965,743.

Specification of Letters Patent. Patented July 26, 1910.

Application filed April 15, 1909. Serial No. 490,098.

To all whom it may concern:

Be it known that I, FREDERICK P. POOLE, a citizen of the United States of America, residing in the city of Bridgeport, in the county of Fairfield, in the State of Connecticut, have invented a certain new and useful Improvement in Electric-Lamp Sockets, of which the following is a specification.

10 The object of my invention is to produce a simple construction of key socket for electric incandescent lamps, with a double break of the circuit when the key is turned to cut off the current.

15 In the accompanying drawings Figure 1 is a side elevation of the internal parts of a socket embodying my invention, the shell and cap being shown in dotted lines; Fig. 2 is a view from the opposite side, the shell 20 and cap not being indicated; Fig. 3 is an inverted perspective view; Fig. 4 is a sectional view; Fig. 5 is a similar view with the key socket turned to the closed position.

I have shown my invention as embodied 25 in a socket of the well known Tournier single button type (Tournier Patent No. 559,232) that is to say, the porcelain or other insulating body A is in a single button or single piece, with a transverse chamber a 30 for the key stem B mounted in a metal frame F, and upon the end of the porcelain is supported the usual screw shell S to receive the lamp base. The usual central contact is on the inner free end of a binding post or arm D, Fig. 2, mounted in a recess in the side of the porcelain body with a binding screw d for one of the wires. The inner end of this arm D projects into the interior of the screw shell through the usual 35 side opening x formed there for the purpose, Fig. 2.

The key stem B has the usual handle b, Fig. 4, and near the opposite end, within the frame F, it carries the usual oblong cam or switch block b¹ with lost motion, this cam or switch piece being of conducting material. The adjacent end of the stem has some freedom of motion in its bearing slot f in the frame, Figs. 1 and 3. A spring- 45 actuated plate E, which in this case is itself a bent spring secured at e to the frame F, bears at its free end against the cam or tumbler b¹, tending to press it toward the screw shell. When the key is turned to close the 50 circuit, one end of the oblong cam b¹ will

bear against the flanged end of the shell as shown in Fig. 5. At the same time the other end of the cam will have pressed the free end of the spring E into contact with a spring finger K, (Fig. 5), which is in electrical contact with, but clamped to the insulating body by the terminal plate or binding post P, for the second conductor. When the key is turned to cut off the current, the circuit is broken at two points, namely, 60 where the switch block leaves the screw shell S and where the spring F leaves the contact finger K, Figs. 1 and 4. The spring E bearing upon the switch block maintains it in the "off" position, while the frame F 65 supports the key stem against the push of the spring.

I claim as my invention—

1. An electric lamp key socket, comprising an insulating body and screw shell and center contact, in combination with wire terminals, a key stem and a switch block mounted on said stem with lost motion, a spring to act on the switch block, a contact carried by the insulating body, and a spring- 75 actuated plate to make connection with said contact, the switch block acting to close the circuit through said contact and to break it with a double break.

2. An electric lamp key socket, comprising an insulating body and screw shell and center contact with two binding posts in combination with a spring contact carried by the insulating body, a conducting switch block interposed between the said spring 80 contact and the shell and adapted to make and break connection on both sides of the switch block, and a spring to act on the switch block.

3. An electric lamp key socket, comprising an insulating body, screw shell and center contact in combination with wire terminals, a key stem, a spring contact carried by the insulating body, a spring-actuated plate to make connection with said 90 contact, and a switch block on the key stem acted on by said spring-actuated plate, as and for the purpose described.

In testimony whereof I have signed my name to this specification, in the presence 105 of two subscribing witnesses.

FREDERICK P. POOLE.
